G. E. NOYES, OF WASHINGTON, DISTRICT OF COLUMBIA, ASSIGNOR TO HIMSELF
AND E. N. GRAY, OF SAME PLACE.

Letters Patent No. 95,374, dated September 28, 1869.

IMPROVEMENT IN CLAY-TEMPERING MACHINES.

The Schedule referred to in these Letters Patent and making part of the same.

To all whom it may concern:

Be it known that I, G. E. NOYES, of Washington, in the District of Columbia, have invented a new and useful Improvement in Machines for Tempering Clay and other substances; and I do hereby declare that the following is a full, clear, and exact description thereof, reference being had to the annexed drawings, making part of this specification, in which—

Figure 1 is a plan or top view of my improved machine, showing the receptacle for the clay or other substance to be tempered, the wheel for acting upon such substance, and the gearing for driving the same.

Figure 2 is a vertical sectional elevation, taken on line $z-z$ of fig. 1, showing the arrangement of gearing for driving the tempering-wheel from below the bed or receptacle in which the material to be tempered is to be placed.

Figure 3 is an elevation of the pinion to be used in propelling the tempering-wheel, together with a portion of the segment-wheel, or wheel with which it meshes, as they are usually constructed.

Figure 4 is a similar view of the same parts, as they appear when constructed in accordance with my invention.

Corresponding letters refer to corresponding parts in the several figures.

This invention relates to machines for tempering clay to be manufactured into bricks, and for other similar purposes; and

It consists in the construction of the pinion which propels the tempering-wheel, as will be more fully explained hereinafter.

Serious difficulties have been encountered in constructing and operating machines of this class, from the fact that the power which has propelled them has been communicated through some horizontal shaft above the receptacle for the material to be tempered, which arrangement has necessitated the use of a long vertical shaft to communicate the motion of such horizontal shaft to the shaft and gear-wheels which propel the tempering-wheel. This arrangement of the parts has rendered necessary expensive, and, in many cases, inconvenient frame-work to support the shafting, which often interferes with the efficient operating of the machine, and is always a large addition to its cost.

Another, and a very serious objection has arisen from the fact that the pinion which meshes into the gear upon the upper surface of the bed or receptacle for the material to be tempered, has been constructed in accordance with well-known rules as to its diameter, and as to the "pitch"-line of its cogs or teeth, which form of construction has been found to be defective in this particular case. It is the design of this invention to remedy the evils above alluded to, which result is accomplished in the manner soon to be described.

A, in the drawings, represents a bed or receptacle for the material to be tempered, which may be of wood, bricks, stone, iron, or any other suitable material, and should be of the form shown in fig. 2, or some equivalent form. This bed or receptacle may be lowered into the earth to a point near the segment-gear upon its upper surface, which position will greatly facilitate the filling of the same, or it may be placed upon a foundation of any kind, and be elevated to any required height to give ready access to the gearing upon the lower end of shaft H. The dimensions of this receptacle will vary according to circumstances, very good proportions for one for tempering clay, for manufacturing into bricks, being twenty feet in diameter by two feet deep.

B represents the annular space to be formed in the receptacle.

C represents the gear, which is to be secured to the upper surface of the receptacle A, its teeth or cogs being upon its upper surface. This gear may be made in segments, and such segments joined together at their ends, to as to form an entire circle, or it may be cast in one piece. Any required pitch may be given to the cogs of this wheel, that will give them the required strength.

D represents the pinion, which meshes into the wheel C, the usual method of constructing which is shown in fig. 3. It has been found, however, that for this particular purpose, a wheel so constructed is very defective, for the reason that it will not remain in gear with the wheel C when propelling the tempering-wheel, for the reason that the contact-surface is only upon the front face of the cogs of wheel C, or that surface which is in the direction of the motion of the pinion. This being the case, the tendency is to lift the pinion out of gear with the wheel C, thus causing a stopping of the tempering-wheel, and endangering the breaking of the gearings. To remedy this defect, I construct the pinion D, as shown in fig. 4, the change consisting in adding to its diameter about one-half of an inch—when the diameter of the pinion is, say, ten inches—but retaining the same number of teeth or cogs, so that each cog of the pinion, as it enters the space between the cogs of the wheel C, shall reach so far forward as to come in contact with the rear faces of the cogs of such wheel, and thus be forced into such spaces, instead of being lifted out, as in the former case. To effect this, it will be necessary to slightly reduce the size of the cogs in such pinion.

E represents a shaft, to the outer end of which the pinion D is secured, its opposite end resting in the bearing I, which is secured to the vertical shaft H.

F represents a bevelled-gear wheel, which is secured to the inner end of the shaft E, and meshes into, and is driven by the wheel G, which is secured to the up-

per end of the shaft H, or to such portion thereof as to cause it to mesh with wheel E, and drive the same.

H represents a vertical shaft, which has its bearings in boxes or sockets secured to the centre of the receptacle A, but which extends down through such receptacle for some distance, and has secured to its lower portion a wheel, G', which meshes into any driving-wheel which may be supplied for the purpose.

I represents a box or bracket, the lower horizontal portion of which embraces the vertical shaft H, and revolves thereon. The horizontal portion of this bracket extends outward from shaft H for some distance, where it joins the vertical portion thereof, which vertical portion is provided with a slot in which the bevelled wheel F works, that portion of said bracket which is inside of this wheel serving as the support and bearing for the inner end of shaft E, while that portion thereof which is outside of such wheel has a slot formed in its upper end, through which the shaft E passes. To this outside portion there is to be secured a box or bearing for the inner end of shaft K to revolve in. The arrangement of these parts is such, that as the vertical shaft H is revolved, the bevelled-gear wheel G, upon its upper end, engages with, and revolves the wheel F upon shaft E, which causes it to revolve upon its axis, and also to perform revolutions around such shaft, in which movement it carries with it the bracket I, the shaft K, with its tempering-wheel K', and disk or wheel which supports the outer end of the shaft upon which it is placed.

K represents the shaft above alluded to, its inner end having its bearing in a box secured to the bracket I, while its outer end is supported upon a blank wheel which rotates with such shaft, and upon a track formed upon the segment-wheel C inside of the cogs of such wheel; or, if preferred, such track may be upon the outside of such cogs.

K' represents a wheel which is to be used as the tempering-wheel. The bed or receptacle having been filled with clay or other substance, and a sufficient quantity of water or other moistening-material having been added, the wheel K' is made to rotate, and thus the material in such bed or receptacle is thoroughly mixed, and made of the same consistency throughout. It will be seen, upon reference to fig. 1, that the rims of this wheel consist of two parts, which form

of construction leaves a recess or groove between such rims at all parts except where they join the spokes of the wheel. The wheel thus constructed presents two cutting-surfaces to any substance with which it comes in contact, and at the same time permits that portion of the material which enters between such rims or flanges to pass through such rims and mingle with the mass upon the outsides. In practice, this wheel is to be loose upon its shaft, so as to be capable of having imparted to it a longitudinal movement thereon, so that, as it revolves around the vertical shaft, it may be forced inward or outward upon its shaft, and thus be brought in contact with all the material in the receptacle. The longitudinal movement spoken of, may be imparted to this wheel by means of a rack and pinion, so arranged that the rotation of the vertical shaft shall give to it the required movement; or, it may be given by a screw so arranged as to be driven from the same shaft; in either case the gearing which drives it being so arranged, that when the tempering-wheel reaches the outside or inside of its range of motion—which will be the inside surface of the receptacle, or the hub at its centre—it shall be reversed, and the tempering-wheel be moved in the opposite direction upon its shaft.

L represents a rod or chain, which is attached to the outer end of shaft E, or to a point just inside the pinion D, from which point it extends to the outer end of shaft K, to which it is secured. This rod is to be attached to the shaft E in such a manner that said shaft shall revolve freely therein, so that, as such shaft revolves, it shall, by acting upon such connection, draw after it the shaft K, and consequently the tempering-wheel K'.

Having thus described my invention,

What I claim, and desire to secure by Letters Patent, is—

The construction of the pinion D, substantially as and for the purpose set forth.

In testimony whereof, I have signed my name to this specification, in the presence of two subscribing witnesses.

G. E. NOYES.
